QUICK ACTING VISE

Joseph Malesko, Dayton, Ohio, assignor of forty-nine percent to William Rentas, Dayton, Ohio
Filed Mar. 15, 1960, Ser. No. 15,143
3 Claims. (Cl. 269—182)

This invention relates to an improved vise, and, in particular, to an improved vise having means for quickly clamping, or releasing an article to be held by the vise.

Generally, when a conventional vise is being used, various sized articles are desired to be subsequently held by the vise. However, since relative movement between the vise jaws is only effected by rotation of the screw shaft, considerable time is spent in varying the distance between the vise jaws to accommodate articles of different sizes.

According to this invention, an improved vise is provided whereby one of the vise jaws can be freely moved toward or away from the other vise jaw without rotating the screw shaft. In this manner, the vise of this invention can be quickly adjusted to receive a desired size article, and then the vise jaws can be subsequently tightened against the article by rotating the screw shaft in the conventional manner.

Therefore, it is an object of this invention to provide an improved vise.

It is another object of this invention to provide an improved vise that is relatively inexpensive to manufacture, has a minimum of parts, and is durable and rugged.

Another object of this invention is to provide an improved vise having means to selectively vary the distance between the vise jaws thereof by a free sliding action between the parts thereof without requiring that the screw shaft be rotated to vary such distance.

Other objects, uses, and advantages are apparent from a reading of this description and/or the accompanying drawings wherein:

FIGURE 1 is a side view of an improved vise of this invention, certain of the parts thereof being shown in section.

FIGURE 2 is an exploded perspective view of the vise illustrated in FIGURE 1.

FIGURE 3 is a view similar to FIGURE 1 and illustrates another embodiment of this invention.

FIGURE 4 is a fragmentary sectional view of the device illustrated in FIGURE 3 and is taken on line 4—4 thereof.

FIGURE 5 is an exploded perspective view of certain of the parts of the device illustrated in FIGURE 3.

Reference is now made to the accompanying drawings wherein like reference numerals are utilized throughout the various figures thereof to designate like parts where appropriate, and particular reference is made to FIGURES 1 and 2 illustrating an improved vise of this invention that is generally indicated by the reference numeral 10.

The vise 10 includes a screw shaft 11, a handle 12 for rotating the shaft 11, and a pair of vise jaws or members 13 and 14 carried by the shaft 11. The vise jaws 13 and 14 are adapted to receive an article 15 therebetween by pulling outwardly on a movable member 16 to permit free sliding of the shaft 11 and the jaw 13 toward the vise jaw 14 to clamp the article 15 between the jaws 13 and 14. Subsequently, the shaft 11 is rotated in a direction to draw the jaws 13 and 14 tightly against the article 15 whereby the article 15 is securely held by the vise 10.

In particular, the screw shaft 11 is provided with an enlarged bifurcated end 17, hereinafter referred to as the turning end, comprising two spaced legs 18 and 19 defining a slot 20 therebetween. The substantially flat handle 12 has an end 21 received in the slot 20 of the shaft 11

2

and is pivotally secured to the legs 18 and 19 by a pin 22. In this manner, the shaft 11 may be rotated by the handle 12 regardless of the angular position of the handle 12 relative to the shaft 11.

Further, should the vise 10 be mounted so that the handle 12 can not be readily rotated through 360° when disposed at an angle relative to the shaft 11, the handle 12 can be moved through an arc of 180° thereby rotating the shaft 11 through 180°. Subsequently, the handle 12 can be pivoted in the slot 20 back to its original position to repeat the partial rotation of the shaft 11. Thus the vise 10 may be mounted on a flat surface or the like without having the handle 12 extend beyond the edge thereof in the conventional vise mounting manner.

The screw shaft 11 has a smooth cylindrical portion 23 adjacent the turning end 17 thereof and an externally threaded portion 24.

The vise jaw 13 has the general shape of a right angled parallelepiped and is substantially rectangular in cross-section and has a pair of opposed sides 25 and 26, the side 26 being suitably recessed by horizontally and vertically extending article holding grooves 27. A bore 28 passes longitudinally through the vise jaw 13 for receiving the shaft 11, the internal diameter of the bore 28 being slightly larger than the external diameter of the shaft 11 whereby the vise jaw 13 is freely axially moved on the shaft 11 and the shaft 11 is freely rotatable relative to the jaw 13.

A bushing 29 is disposed on the shaft 11 between the enlarged portion 17 thereof and the vise jaw 13 to provide a suitable bearing means therebetween.

The vise jaw 14 is substantially of the same size as jaw 13 and also has the same general shape of a right angled parallelepiped and is also substantially rectangular in cross-section and has a pair of opposed sides 30 and 31, the side 31 being provided with horizontally and vertically disposed article holding grooves 32 in the same manner as the vise jaw 13. A bore 33 passes longitudinally through the vise jaw 14 in a manner similar to the bore 28, the bore 28 being of a size to permit free axial movement of the jaw 14 on the shaft 11.

An opening 34 is also formed in the vise jaw 14, the opening interrupting the side 30 there and angularly intersecting the bore 33. The opening 34 defines an angularly disposed surface 35 of the vise jaw 14.

The movable member 16 has a portion thereof disposed in the opening 34 of the vise jaw 14, the member 16 having a surface 36 disposed in sliding engagement with the surface 35 of the jaw 14. The member 16 is provided with a threaded end or surface 37 adapted to be disposed in threaded or driving relation with the threaded portion 24 of the shaft 11.

Suitable means are provided for interconnecting the movable member 16 to the vise jaw 14 and for maintaining the threaded surface 37 thereof in driving relation with the shaft 11. In the embodiment illustrated in FIGURES 1 and 2 of the drawings, the movable member 16 is provided with an angularly disposed longitudinal slot 38, the slot 38 being disposed parallel to the surfaces 36 and 35 of the member 16 and jaw 14 respectively.

A horizontally disposed pin 39 is carried by the jaw 14 and passes transversely through the slot 38 to interconnect the movable member 16 to the vise jaw 14. A leaf spring 40 is detachably secured to the jaw 14 by a screw 41 and has the outer end 42 thereof disposed in a groove 43 formed in the movable member 16. In this manner the spring 40 maintains the member 16 in the position illustrated in full lines in FIGURE 1 whereby the vise jaw 14 is operatively interconnected to the shaft 11. Thus, upon rotation of the shaft 11, relative movement between

the vise jaw 14 and the shaft 11 is effected by the threaded driving relation thereof.

The movable member 16 is adapted to be moved out of engagement with the threaded portion 24 of the shaft 11 by grasping the free end 44 of the member 16 and pulling the same upwardly to the position illustrated in dotted lines in FIGURE 1 whereby the threaded surface 37 is out of engagement with the shaft 11. In this manner, free sliding movement between the shaft 11 and vise jaw 14 is effected.

In order to facilitate grasping of the free end 44 of the member 16, suitable circular recesses 45 are formed in opposed sides of the member 16.

As illustrated in FIGURE 1, both vise jaws 13 and 14 are provided with semi-circular cut out portions 46 at opposite sides thereof, the cut out portions 46 defining flat mounting surfaces 47 having vertical bores 48 passing therethrough. In this manner either vise jaw 13 or 14 is adapted to be mounted to a suitable support means, and, in the embodiment illustrated in FIGURE 1, the vise jaw 14 is mounted to a bracket 49 by bolts 50. The bracket 49 is, in turn, detachably mounted to the edge of flat surface, such as a work bench top 51.

The operation of the vise 10 illustrated in FIGURES 1 and 2 will now be described. When it is desired to move the vise jaw 13 toward the non-movable vise jaw 14 in order to clamp the work piece 15 therebetween, the movable member 16 is pulled outwardly to the position illustrated in dotted lines in FIGURE 1 and the shaft 11 is moved to the right sliding freely in the bore 33 of the vise jaw 14. Since the bushing 29 engages the side 25 of the vise jaw 13, movement of the shaft 11 to the right causes the vise jaw 13 to be carried therewith.

When the shaft 11 and jaw 13 have been moved the desired distance to the right to abut the article 15 disposed between the jaws 13 and 14, the movable member 16 is released and the spring 40 returns the same into driving relation with the threaded portion 24 of the shaft 11. Thereafter, the shaft 11 is rotated by the handle 12 to cause the shaft 11 and thus the jaw 13 to be further moved to the right to securely clamp the article or work piece 15 between the jaws 13 and 14.

Similarly, should it be desired to increase the space between the jaws 13 and 14 to receive a relatively large article 15, the operator merely pulls the member 16 upwardly to disengage the same from the shaft 11 and pulls the jaw 13 to the left, the jaw carrying the shaft 11 therewith through the abutting relation of the jaw 13 with the bushing 29. When the desired space between the jaws has been reached, the member 16 is released to permit rotation of the shaft 11 to draw the jaw 13 toward the jaw 14.

While it is not illustrated, it is to be understood that the jaw 13 could be mounted to the bracket 49 instead of the jaw 14 if desired. With this arrangement, the jaw 14 can be freely moved axially on the shaft 11 when the member 16 is pulled outwardly to disengage the same from the shaft 11.

In this latter arrangement where the jaw 13 is mounted to the bracket 49, the jaw 13 could be mounted to the shaft 11 in a manner to prevent axial movement of the shaft 11 relative to the vise jaw 13 while permitting the shaft 11 to rotate relative to the vise jaw 13.

In particular, such a vise 10' is illustrated in FIGURES 3-5 wherein like reference numerals are utilized to designate similar parts of the vise 10 previously described except that the like reference numerals are followed by a prime mark.

The vise jaw 13' is fixed to the shaft 11' by a vertically disposed pin 52 passing through a bore 53 formed in the jaw 13', the pin 52 passing immediately above an aligned annular reduced portion 54 of the shaft 11'. In this manner the shaft 11' is prevented from being moved axially of the vise jaw 13' while still being rotatable rela-

tive thereto. As illustrated in FIGURES 3 and 4, the vise jaw 13' is mounted to the bracket 49' by bolts 55 while the vise jaw 14' is movable relative to the shaft 11' and bracket 49'.

5 The movable member 16' is interconnected to the vise jaw 14' in the same manner as previously described except that instead of the leaf spring 40, a coiled spring 56 is received in the slot 38' thereof. The spring 56 has one end thereof disposed in a recess 57 formed at 10 the bottom of the slot 38' and the other end disposed in abutting engagement with the pin 39' carried by the vise jaw 14'.

The operation of the vise 10' illustrated in FIGURES 3-5 will now be described. When it is desired to decrease the space between the vise jaws 13' and 14' to clamp an article 15' therebetween, the movable member 16' is pulled upwardly to disengage the same from the threaded portion 24' of the shaft 11' whereby the jaw 14' can be freely moved axially on the shaft 11' toward the jaw 13'. Similarly, the jaw 14' can be freely moved away from the jaw 13' until the desired distance between the jaws 13' and 14' has been reached.

Subsequently, the movable member 16' is released and the spring 56 returns the member 16 to the position illustrated in full lines in FIGURE 3 whereby the jaw 14' can be moved to and from the jaw 13' by rotating the shaft 11'.

In either of the embodiments above described, rotation of the shaft 11 or 11' causes the member 16 or 16' to be moved downwardly into further engagement with the threaded portion 24 or 24' of the shaft 11 or 11' when the jaw 14 or 14' is being held from movement. This feature is accomplished by the wedging action produced between the surfaces 36 or 36' and 35 or 35' of the member 16 or 16' and jaw 14 or 14'.

Therefore, it can be seen that vises are provided that have means for rapidly and readily varying the distances between the vise jaws thereof without rotation of the screw shafts thereof. However, while the term vise has been utilized, it is to be understood that other holding devices can be made according to the teachings of this invention, such as lathe tool holders and the like.

It is to be understood that the vise jaw arrangement 14' of FIGURES 3-5 can be utilized with the vise jaw arrangement 13 of FIGURES 1 and 2, and the vise jaw arrangement 13' can be utilized with the vise jaw arrangement 14 is desired.

Further, either vise jaw 13 or 14 or vise jaw 13' and 14' can be detachably and directly secured to a flat surface or support means by screws or bolts 50 or 55 passing through openings 47 in the respective member. For example, the particular vise jaw can be directly secured to a work bench, a drill press, table or other suitable support means without utilizing the intermediate bracket 49 or 49'.

It is also to be understood that the vise arrangements 10 and 10' or the various combinations thereof are also very useful when the same are not attached to a support means or the like. In particular, the flat bottoms of the jaws 13, 14, 13' and 14' can rest on any flat surface while the same hold an article therebetween. In this manner the article held by the vise jaws can be held more firmly by the vise even though the vise is merely resting on a flat surface or the like. For example, the unattached vise can be utilized to firmly hold a work piece on a drill press table.

While the forms and embodiments now preferred have been disclosed in accordance with the statute, it is to be understood that other forms and embodiments may be employed, all coming within the scope of the appended claims which follow.

What is claimed is:

1. A vise comprising a pair of aligned substantially equally sized vise jaws both of which have the general shape of a right angled parallelepiped, both having

aligned and similar bores passing therethrough, one of said vise jaws having an opening adjacent one end of said vise and interconnected with said bore thereof, said opening having a wall defining a surface that angularly intersects said bore thereof, a rotatable shaft passing through said bores and having a turning end and a threaded portion, a movable member disposed in said opening and having a threaded surface at one of its ends adapted to threadedly engage said threaded portion of said shaft to permit driving movement between said one jaw and 10 said shaft when said shaft is rotated and said member is in a first position relative to said one jaw, said member having a portion extending out of said one end of said vise adapted to be pulled out to permit free sliding movement between said one jaw and said shaft when said member is in a second position, said member having an elongated slot passing therethrough and angularly disposed relative to said shaft, said one vise jaw carrying a pin that extends transversely through said slot in said member whereby said pin controls angular movement of 15 said member toward and away from said shaft, and spring means carried by said vise and engaging said member to tend to urge said member toward said shaft.

2. A vise as set forth in claim 1 wherein said member

5 has a surface disposed in sliding engagement with said surface of said one jaw to cause wedging movement of said member toward said shaft when said one jaw is tended to be moved away from said other vise jaw.

3. A vise as set forth in claim 1 wherein said portion has opposed recesses for readily grasping said portion.
